OPERATING MECHANISM FOR INJECTOR
OVERFLOW VALVESEmanuel Rawson, Chicago, Ill., assignor to The
Superheater Company, New York, N. Y.

Application April 2, 1938, Serial No. 199,576

5 Claims. (Cl. 103—275)

This invention relates to injectors and has particular reference to exhaust steam injectors for steam locomotives. Still more particularly the invention relates to means for holding the overflow valve of such an injector closed when it is desired to blow steam into the water suction line to clear it or the suction strainer of obstructions and also to prevent the escape of steam admitted to the injector to prevent freezing while out of operation during cold weather.

One type of mechanism heretofore employed to hold the overflow valve closed for the purposes mentioned consists of a spindle threadedly mounted in a bracket on the injector casing in alignment with the overflow valve stem so that the spindle may be screwed down to operatively engage the valve stem for positively holding the valve closed. Due to the fact that the injector is mounted beneath the locomotive cab and the controls therefor are mounted in the cab, it has been customary to interpose a series of rotatable rods interconnected by universal joints between the aforesaid spindle on the injector casing and the control wheel or handle in the locomotive cab.

Although this mechanism is operated only occasionally to provide for blowing back of the suction line or heating of the injector, it is nevertheless subjected to considerable wear due to vibration because the jointed construction of such a valve operating mechanism results in vibration producing wear of the parts.

An object of the present invention is to provide an improved mechanism for operating the overflow valve in which wear due to vibration is substantially eliminated.

Another object of the invention is to provide means for protecting delicate mechanism such as indicating gauges or control operating bellows associated with the injector against excessive steam pressures within the injector when live steam is admitted to the latter while the overflow valve is held closed either to blow back the suction line or prevent freezing of the injector.

In the drawing:

Fig. 1 is a diagrammatic representation of part of a locomotive equipped with an injector embodying the present invention;

Fig. 2 is an enlarged sectional view on the line 2—2 in Fig. 1; and

Fig. 3 is an enlarged sectional view on the line 3—3 in Fig. 2 showing certain details of the injector construction.

Referring to Fig. 1, the numeral 10 designates the boiler of a locomotive at the rear end of which is the cab 11. Located beneath the cab is an exhaust steam injector, indicated generally at A, which for purposes of illustration is shown as being as the kind shown and described in United States Patent 1,870,006, granted August 2, 1930, to Malcolm Hard, to which reference may be had

for details of construction not described herein. It will be understood that the present invention is also applicable to other types and kinds of injectors, including live steam injectors.

Exhaust steam is supplied to the injector A from the exhaust passages of the locomotive cylinders through pipe 12. Live steam is supplied from the boiler turret 13 through the live steam supply pipe 14 for operating the injector in conjunction with exhaust steam, for operating the injector as live steam injector when exhaust steam is not available, for clearing the suction line of obstructions or for heating the injector to prevent its freezing. Flow of steam through pipe 14 is regulated by the remote control valve 15 located in a convenient position in the cab of the locomotive. Water is supplied to the injector from the locomotive tender (not shown) through the suction pipe 16 and the amount of water supplied to the injector is controlled by means of the operating handle 17 also located in the locomotive cab. A dual gauge 20 in the locomotive cab is connected by gauge pipes 21 and 22 to the low pressure chamber 23 (Fig. 2) and the overflow chamber 24, respectively, of the injector so that observation of the two needles of the gauge may serve to inform the fireman of the conditions under which the injector is operating. The injector is also provided with an exhaust pressure regulator for automatically controlling the amount of exhaust steam supplied to the injector in order that the maximum amounts of exhaust steam may be utilized under various conditions of operation. As described in copending application Serial No. 185,548, filed January 18, 1938, this regulator consists of a bellows device 25 subjected through a pipe 26 to the pressure existing in the overflow chamber 24 of the injector. An increase of pressure in the overflow chamber results in compressing the bellows 25 which then acts to close a butterfly valve 27 in a passage 28 leading to the space between the draft nozzle 30 and the vacuum nozzle 31 of the injector.

The passage from the overflow chamber 24 to the overflow pipe 32 of the injector is controlled by an overflow valve 33 (Fig. 3) which rests upon a seat at the upper end of the chamber. When the injector is functioning normally and delivering water, the delivery pressure is communicated to a piston 34 which acts through a lever 35 engaged with the stem 36 of overflow valve 33 to hold the latter closed. In the absence of delivery pressure, piston and lever are held in retracted position by a spring 37.

The details of construction described above relate mainly to the normal operation of the injector and do not, per se, form a part of the present invention. For the purpose of positively closing the overflow valve when it is desired to clear the suction line or prevent freezing of the

injector, the following mechanism is provided. Supported on a bracket 40 on the injector casing is a cylinder 41 open at its lower end and containing a plunger 42 which is aligned with the stem 36 of valve 33. A spring 43 mounted between a shoulder 44 on plunger 42 and another near the base of the cylinder bore is provided for moving the plunger into engagement with lever 35 which overlies the end of the stem 36 of the overflow valve. The inner end of plunger 42 is connected to one end of a cable 45 closely fitting within a flexible sheath or tube 46 and extending to a convenient location within the locomotive cab. At the cab end the cable is connected to a threaded slide or spindle 47 mounted in a bracket 48 and held against rotation by a stud 50 carried by the bracket and engaging a longitudinal groove 51 in the spindle. A hand wheel 52 threaded on the spindle 47 is held against bracket 20 48 by spring 43 acting through cable 45. When the hand wheel 52 is turned clockwise it causes movement of the spindle 47 to the left, Fig. 3, and retracts the plunger 42 from engagement with the lever 35 which lies between the end of 25 the plunger and the valve stem 36. This action results in compressing the spring 43 so that it holds the plunger 42, the cable 45 and the spindle 47 under tension and thus minimizes wear of these parts due to vibration by holding them 30 against any substantial movement.

When it is desired to admit live steam to the injector either for the purpose of clearing the suction line or to prevent freezing of the injector, the overflow valve 33 must be held in closed position. To accomplish this the hand wheel 52 is turned counter-clockwise and this results in spring 43 acting to move the plunger 42 into operative engagement with the lever 35 which contacts the stem 36 of the overflow valve. As 35 the hand wheel is operated to permit plunger 42 to be projected from the cylinder 41 to hold the overflow valve closed, the load of the spring 43 is transferred from plunger 42 to the overflow valve 33. The initial compression of spring 43, when 40 the plunger is releasably held in retracted position, is such that when the load of the spring has been transferred to valve 33 sufficient energy remains stored in the spring so that it functions as a load for the overflow valve. Consequently, 45 the overflow valve is converted to a relief valve which serves to protect the indicating gauge 20 and the bellows 25 against excessive pressure when valve 15 is opened to supply live steam to the injector. If during the time that steam is 50 being admitted to the injector while overflow valve 33 is closed for the purpose of blowing back the suction line or heating the injector, a pressure should be built up in the injector which might result in injury to the gauge 20 or bellows 25, the overflow valve 33 opens automatically at 55 the time the pressure exceeds the load afforded by the spring 43.

Although an illustrative embodiment of the invention has been shown and described in detail herein it is to be understood that various changes and variations may be made without departing from the invention, and therefore it is intended to include all such changes and variations within the scope of the appended claims.

70 What I claim is:

1. In an injector having a normally closed overflow valve controlling communication between its overflow chamber and its overflow pipe;

a plunger movable to operatively engage said valve for holding it closed; a spring acting on said plunger to move it for operatively engaging said valve; a cable attached at one end to said plunger; means associated with the other end of said cable operable to move said plunger to a retracted position out of operative engagement with said valve and acting to energize said spring so that it holds said plunger and cable under tension to eliminate vibration thereof. 10

2. In an injector having a normally closed overflow valve controlling communication between its overflow chamber and its overflow pipe; a plunger movable to operatively engage said valve for holding it closed; a cable attached at one end to said plunger; releasable means associated with the other end of said cable for holding said plunger in a retracted position out of said operative engagement with said valve; and a compression spring mounted between said plunger 20 and a fixed support and acting to maintain said plunger and cable under tension for eliminating vibration, said spring acting upon release of said holding means to move said plunger into operative engagement with said valve and to hold the latter closed. 25

3. In an injector having a normally closed overflow valve controlling communication between its overflow chamber and its overflow pipe; a plunger movable to operatively engage said 30 valve for holding it closed; a cable attached at one end to said plunger; releasable means associated with the other end of said cable for holding said plunger out of operative engagement with said valve; and a spring acting on said 35 plunger, upon release of said holding means, to move it into operative engagement with said valve, the force stored in said spring being such that after it moves said plunger to operative engagement with said valve it retains sufficient 40 energy to constitute a load for said valve.

4. In an injector having a normally closed overflow valve controlling communication between its overflow chamber and its overflow pipe; a movable plunger positioned out of operative 45 engagement with said valve; a spring urging said plunger into operative engagement with said valve to hold it closed; a cable attached at one end to said plunger; and means associated with the other end of said cable operable to move and hold said plunger in its retracted position out of operative engagement with said valve and acting to energize said spring so that it holds said plunger and cable under tension to eliminate vibration thereof. 55

5. In an injector having a normally closed overflow valve controlling communication between its overflow chamber and its overflow pipe, means for admitting steam to the interior of said injector including said chamber thereof, and means in communication with the interior of said injector and responsive to pressure conditions therein; a member operable to hold said valve in closed position when the injector is out of operation and it is desired to retain steam under pressure within the injector; and a spring associated with said member and valve and acting, when said member is effective to close said valve, as a yieldable load for said valve to protect said pressure responsive means against excessive 60 steam pressures within said injector. 70
